UNITED STATES PATENT OFFICE.

JOHN F. McCARTHY, OF NEW YORK, N.Y.

THREE-WAY PULL-CHAIN SOCKET.

1,238,540.

Specification of Letters Patent. Patented Aug. 28, 1917.

Application filed December 29, 1916. Serial No. 139,500.

To all whom it may concern:

Be it known that I, JOHN F. McCARTHY, a citizen of the United States, and a resident of the city of New York, borough of Manhattan, in the county and State of New York, have invented a new and Improved Three-Way Pull-Chain Socket, of which the following is a full, clear, and exact description.

10 This invention relates to an electrical socket and particularly to a socket to be used in connection with a switch or another socket of a similar nature whereby the light connected with the socket may be turned on 15 at one place and turned off at another.

The object in view is to provide an improved socket for electric lamps which will dispense with one switch when it is desired to turn the light off and on at two different 20 places.

Another object in view is to provide a pull switch which has three ways whereby the same may coact with an ordinary three-way switch.

25 In the accompanying drawing:—

Figure 1 is a longitudinal vertical section through a three-way pull chain socket disclosing an embodiment of the invention.

Fig. 2 is a fragmentary sectional view 30 through Fig. 1 on line 2—2.

Fig. 3 is a view similar to Fig. 2 but with the switch arms in a different position.

Fig. 4 is a plan view through a switch of ordinary construction, the casing being removed.

Fig. 5 is a diagram showing the wiring and arrangement of the switches disclosed in Figs. 1 and 4 associated therewith.

Referring to the accompanying drawing 40 by numerals, 1 indicates a casing of any desired kind provided with an insulating jacket 2 of the usual construction for the ordinary two-way pull chain socket now in common use. As shown in Figs. 1, 2 and 3,

45 the construction is the same as an ordinary two-way pull chain socket except for the certain additions and changes necessary to produce a three-way pull chain socket with the characteristics shown in the drawing.

50 In forming the mechanism of a pull socket a pivotally mounted switch member 3 is provided which is formed with arms 5 and 6 designed to engage the contacts 7, 8 and 9 at different times, contacts 7 and 8 being comparatively small while contact 9 is sufficiently large to allow one of the arms 5

and 6 to rest thereon while resting on either of the contacts 7 or 8, as clearly illustrated in Figs. 2 and 3. This construction is different from the ordinary two-way pull 60 socket in that the contact 9 is longer than the others and arranged to contact as just described. Also, in arranging the present invention or attaching the same to an ordinary two-way pull chain socket, the current 65 is brought in through wires 10 to a contact plate 11, which contact plate has the lower part held in position by the screw 12, which screw engages the center of the lamp in the usual manner so as to transmit current 70 to the lamp, and from the lamp the current will pass to the sleeve 13 and from said sleeve to contact 9.

As shown in Fig. 5, a source of current 14 is connected to the binding post 15 on a 75 switch 16 and to the contact plate 11 through wire 10. The switch 16 is the ordinary switch now in common use and will need no detail description, except that the wire 14 leads to the binding post 15 and 80 said binding post is connected to the contact 17 by a suitable wire so that current is always supplied to the contacts or binding posts 15 and 17 and is switched alternately on to the contacts 18 and 19 according to the position of the arm 20. Contact 18 is connected by wire 21 to the contact 8, while contact 19 is connected through wire 22 to the contact 7. It will also be noted that the lamp is connected at its center to 90 the contact plate 11 by engaging the screw 12 and the shell of the lamp is connected to the contact 9 while engaging the sleeve 13 which is connected by a suitable wire to the contact 9.

When the parts are in the position shown in Fig. 5 current will pass from the wires 14 to the contacts 15 and 17 through the switch arm 20, contact 19 and wire 22, contact 7 to arms 5 and 6 of switch member 3, 100 contact 9, and from thence through the lamp and from the lamp out through wire 10 back to the source of current. If the switch member 3 is turned to the position shown in Fig. 2 current will pass from the source 105 14 to contact 15 and from thence through the switch arm 20, contact 18, wire 21, contact 8, switch member 3 and associated parts, and from thence through the lamp and back to the source. When it is desired 110 to shut off the light when the parts are arranged as shown in Fig. 5, either the pull

socket member is operated or the switch 16. If the switch 16 is operated the lamp will be deprived of current and may be again supplied by operating either switch.

- 5 This arrangement will dispense with one switch now in ordinary use where a lamp is lighted and turned out from two different places, as for instance, down stairs and up stairs in a dwelling. By using the three-
10 way pull chain socket described and a switch as shown in Fig. 4, the same result may be accomplished as if two switches were used in the wall.

What I claim is:

- 15 1. A three-way pull chain socket comprising three spaced contacts, one of which is longer than the others, a rotatable contact member having arms and designed to engage said contacts, said arms being of sufficient length that the long contact will always remain in contact with one of said arms while the other arm is in contact with one of the other contacts, means for connecting supply wires to the two short contacts, and a contact plate connected with the source of supply extending to a position to be engaged by the lamp when placed in position in the socket.
20 2. In a switch of the character described, a casing, a pair of spaced contacts arranged in said casing, means for connecting lead wires to said contacts, a contact plate arranged independent of said contacts, means for connecting a supply wire to said contact

plate, a third contact having a comparatively long contact surface, means for connecting a lamp with said last mentioned contact and said contact plate, and a rotatable switch member formed with a pair of arms of substantially the same length, the length of the last mentioned contact being such as to always engage one of said arms when the opposite arm is contacting with one of the other contacts.

3. In a three-way pull chain socket of the character described, a pair of contacts connected to lead-in wires, a third contact of an appreciable length designed to be connected with one side of an electric lamp, a contact bar connected to a lead-in wire designed to be connected to the opposite side of the lamp, and a switch member having a pair of contact arms, said arms being of such length as to engage one of said pair of contacts while the other is engaging the other contact.

4. In a socket of the character described, a pair of contacts arranged to be connected to lead-in wires, a third contact of an appreciable length, a switch member having contact arms arranged to contact with said pair of contacts at different times and said third contact, means for intermittently moving said switch member, a contact plate arranged to be connected to a supply wire, and means for connecting a lamp to said contact plate and said third contact.

JOHN F. McCARTHY.
